UNITED STATES PATENT OFFICE.

EDWARD E. CLEMENT, OF WASHINGTON, DISTRICT OF COLUMBIA, ASSIGNOR, BY
MESME ASSIGNMENTS, TO FREDERICK C. STEVENS, OF ATTICA, NEW YORK

TELEPHONE-EXCHANGE SYSTEM.

1,107,150.

Specification of Letters Patent. Patented Aug. 11, 1914

Application filed November 26, 1906. Serial No. 345,167.

To all whom it may concern:

Be it known that I, EDWARD E. CLEMENT, a citizen of the United States, residing at Washington, in the District of Columbia, have invented certain new and useful Improvements in Telephone-Exchange Systems, of which the following is a specification, reference being had therein to the accompanying drawing.

10 My invention relates to telephone exchange systems and apparatus for use therein.

It has particular reference to semi-automatic systems, although not limited thereto. 15 Its object is to provide certain improvements in such systems, and particularly in the impulse transmitters or sending machines used by operators or subscribers for controlling automatic switching means.

20 The invention comprises the sending machine itself and the circuit therefor. The machine is mechanically driven, normally unwound, with a number wheel having a plurality of sets of teeth on its periphery.
25 and means for short-circuiting any desired number of teeth in each set to determine the number of impulses transmitted thereby. The short-circuiting means in the present case I make push buttons having stems set 30 at intervals and radially around the axis of the wheel. There may be one or more sets of these buttons, and with each set a fin or short-circuiting projection on the spindle operates as the spindle turns, the number of 35 impulses transmitted being determined by the number of teeth passing the contact springs before the same are short-circuited.

The circuit for this machine comprises means for connecting the same to a trunk circuit or operator's cord circuit at the central office, and for disconnecting the same therefrom. The use and connection of the machine at the subscriber's station are of course obvious.

45 The invention is illustrated in the accompanying drawings in which—

Figure 1 is a plan view of the sending machine; Fig. 2 is a similar view with the top of the case and push button mechanism removed; Fig. 3 is a side view looking in the direction of the arrow in Fig. 2, the side of the casing being removed; Figs. 4, 5, and 6 are details of the driving shaft and short-circuiting fin; Fig. 7 is a diagram of the circuit, up to the point of connection of the

first selector switch trunk; Fig. 8 is a continuation of the diagram in Fig. 7, showing the switch circuits. Fig. 8^a is a diagram similar to Fig. 8 showing modified ringing means.

In the drawings I have illustrated one form of embodiment of my invention, which may be generally stated as follows: A calling subscriber's line announces itself to the operator by means of a signal, and the operator thereupon plugs up the line to a trunk leading to an automatic switch outfit; or else the line calling may automatically connect itself to a trunk through what I have called primary selector apparatus, such as is illustrated in my prior application filed September 18th, 1905, Serial No. 279,031. In either case the calling line becomes connected to automatic switching apparatus, but as the subscribers' stations are not provided with any controlling apparatus or "sending machine," some further device and connections at the central office are required in order to complete the connection. I supply this in the form of an operator's sending machine, consisting of a mechanism for sending variable sets of impulses. This mechanism is connected to the trunk and at the same time the operator's telephone is brought into use so that the number wanted may be ascertained. The sending machine is then manipulated to transmit the necessary impulses to actuate the switches so as to effect connection with the line wanted. This sending machine preferably has rows of push buttons for determining the numbers to be sent, and a spring-driven train or

With this preliminary explanation the detailed description may now be readily followed. Before taking up the circuit I will present the apparatus which is shown in Figs. 1 to 6. As already stated this consists of a spring motor and a transmitting wheel.

with certain auxiliary contact devices and push buttons for the latter, all mounted in a case A which is supposed to be secured in the top of an operator's desk, as indicated 5 by the sectional view, Fig. 3. The spring motor is shown at M in Fig. 2, being provided with a main driving spring m^2 , adapted to be wound up by an arm m' having a handle m^3 which projects above the top of 10 the desk as shown in Fig. 3. This arm is rigidly secured to the main arbor or spindle m of the motor, the same being geared up to the usual escapement devices so as to suitably regulate the speed of its rotation. In 15 its normal condition, with the spring unwound, the winding arm lies in the position shown in Figs. 2 and 3, all the working parts of the device being shown in the position of rest.

20 The main arbor m carries the driving wheel m^4 which meshes with the pinion m^5 on the spindle s of the number wheel. This spindle is journaled in the two frame plates a' a' , and the parts are all so proportioned 25 and arranged that each time the arm m' is thrown over to wind up the spring, the motor in running down will rotate the spindle s and all the parts it carries through one complete turn of 360° . The parts carried 30 on the spindle are the number wheel W and the short circuiting fins s' , s^2 , s^3 , and s^4 . As all of these parts must be accurately positioned on the spindle with regard to each 35 other, I will refer here to their mode of attachment, which is indicated in detail in Figs. 4, 5 and 6. The spindle itself is square throughout its length as indicated at s^9 in Fig. 5, but is rounded at its ends as indicated in Figs. 2 and 4, for the purpose of fitting 40 in its bearings. A threaded shoulder is formed on each rounded end, one end receiving the nut s^7 and the other nut s^8 , between which the other parts are clamped. I may state that it is necessary for these 45 parts to be insulated from the spindle, so four slips of insulating material s^{10} are laid on the four faces of the spindle and the wheels and fins are then slipped on, it being impossible for them to turn because their 50 openings are also squared and fit accurately upon the insulation. Fig. 6 shows one of the fins with its square opening. It will be observed that this opening is so placed that its diagonal coincides with the center line 55 or radius of the fin. By this means all the fins can be made with the same punch and die, all can be formed with the same forming tool, and all can be assembled in their respective positions by simply placing the 60 twin parts face to face and then turning the several pairs at angular distances of 90° from each other. As regards the insulation, it is quite obvious that I may use a square tube, and I may remark in passing that the 65 reason for squaring these parts is that there

are four sets of numbers on the wheel. If we have five sets of numbers to transmit, it would be necessary to provide five faces on the shaft and make the openings in the other parts to correspond therewith.

The fins and the wheel are suitably spaced apart on the shaft or spindle by means of tubular distance pieces s^5 , whose configuration, except for their plane ends, is a matter of indifference. Outside of the wheel on 75 the one end and of the hub of the fin on the other end are two washers and beyond these the nuts already referred to. By turning up these nuts the attached parts are firmly clamped together.

The number wheel is best shown in Figs. 2 and 3. It has four sets of ten teeth each, which I have indicated at w^1 , w^2 , w^3 , and w^4 , separated by long spaces or intervals without teeth. Each set of teeth and each interval is equal in its arc dimensions to one-eighth of the entire periphery. The fins s^1 , s^2 , s^3 , and s^4 are spaced apart from each other on the shaft distances equal to the distance apart of the rows of push buttons P^1 , 80 P^2 , P^3 , and P^4 , shown in Fig. 1. Each push button has a stem p^2 mounted to slide through the top of the casing and through openings p^3 and p^4 in the frame pieces p^5 and p^6 . Upon each stem I provide a conical 90 cam p^7 , and alongside of the stem of each row of buttons I arrange a slide plate p^{10} carrying pins p^9 to cooperate with the cams. Each cam has a shoulder p^8 on its upper 95 face, which however is slightly beveled or chamfered off on the edge for the purpose of insuring the restoration of each cam to normal when another cam in the same row is pressed down. The slide p^{10} works in slots cut in the end pieces p' of the frame, and 100 is held normally pressed to the right by means of the steel spring p^{11} which is set into slots cut in the members p^5 and p^6 of the frame.

The stem p^2 are all set radially with respect to the wheel W , and when they are pressed in, their tips must come within the compass of one of the fins s' , etc., with which they cooperate, that is to say, within one-eighth of the circumference. Each row 115 of buttons registers with one of the fins s' , s^2 , etc., and in the complete rotation of the spindle s each fin will make contact throughout its length with whichever stem is down in its set.

120 Mounted on the side of the casing A is a pair of springs c and c' , one of which is electrically connected to the frame and the other is electrically connected to the wheel W by means of the supplemental spring contact w^0 . The purpose of this is that when one of the fins s' , s^2 , etc., touches one of the stems p^2 , the wheel W , which is connected electrically to the fins, will thereby become 125 connected to the frame, hence the two springs 130

c and *c'*, one of which is connected to the frame and the other to the wheel, become connected together, thereby short circuiting any further breaks. These spring are normally in contact, although I may of course change the circuit connections so as to make them normally open. They are adapted to be separated by means of an insulating stud *c* which plays in an opening in the side of the casing, and passed through a corresponding opening in the lower spring *c'*, while having its tip lying close to the periphery of the wheel *W*. When the wheel rotates and its teeth reach this stud, the springs will be opened and closed as many times as there are teeth, remaining closed however while the plain intervals on the wheel are passing. If no other means were provided, therefore, than the wheel and the springs, each complete rotation of the wheel would produce four groups of ten breaks each in the circuit connected to the springs, these groups or breaks being separated by four intervals of equal length, during which the circuit remains closed. In order to vary the number of impulses that may be sent in each group however, I provide the push buttons and their stems, and it will be observed that the springs may be short circuited at any desired point by depressing the corresponding button *p*. When the first button, commencing at the left of Fig. 3 is depressed, and the wheel starts to rotate, there will be one impulse transmitted by the first set of teeth *w'*, for the reason that the fin *s'* will come into contact with the stem of the button at the same time that the second tooth reaches the stud *c'*. As the machine is actually set in the drawing however, four breaks will actually be produced by the first group of teeth *w'*, since the fourth button has been pushed down, and four teeth will therefore pass over the stud *c'* before the fin *s'* reaches the stem *p*² of the button which has been depressed.

On the opposite side of the casing from the springs *c c'* I provide a similar pair of springs *c² c³*, these being arranged however so they are normally out of contact with each other, and are adapted to be brought in to contact by means of a stud *c⁵* passing through the wall of the frame. It will be observed upon reference to Fig. 2 that this stud *c⁵* is not affected by the teeth on the wheel because it is out of alignment therewith. It is intended to be pressed up only four times during a complete rotation of the wheel, this being accomplished by circular cams or studs *w⁵, w⁶, w⁷, and w⁸* screwed to the face of the wheel and projecting beyond the periphery thereof. These studs are located angularly on the wheel in such fashion that they close the springs *c², c³* together at the middle points of the respective intervals between teeth, the result being that

the impulses will be transmitted in this way: (1) a selected number of breaks at *c c'*; (2) a single make at *c², c³*; (3) a selected number of breaks at *c c'*; (4) a single make at *c² c³*; etc.

The operation of my sending device will now be fully understood. The operator sets up the number desired to be transmitted by depressing the corresponding keys shown in Fig. 1, and then pulls toward her the handle *m³*, causing the arm *m'* to turn the arbor *m* and wind up the spring *m²*, so that when the handle is released the motor will run down and turn the wheel *W* and the fins *s', s², s³* and *s⁴* through one complete rotation. We will assume the number selected to be 4468. In Fig. 1 the fourth button in each row *P', P²*, the sixth button in the row *P³* and the eighth button in the row *P⁴* are depressed. As the wheel rotates the set of teeth *w'* coming into contact with the stud *c'* produce four breaks, when the fin *s'* comes into contact with the stem *p²* of the number 4 button in its set, the said stem passes between the two spring leaves or halves of the fin, and the rest of the teeth in the set *w'* are short circuited, because by the time the fin passes off of the button stem the last tooth has also passed the stud. These four breaks *c c'* are followed by a single make at *c² c³* caused by the stud *w⁶*. Next, the teeth *w²* come into engagement with the stud *c⁴*, and likewise produce four breaks before the fin *s²* short circuits them. Then in succession the teeth *w³* reach the stud *c⁴*, and produce six breaks before being short circuited by the fin *s³*. Finally, the teeth *w⁴* reach the stud *c⁴* and produce eight breaks before they are short circuited by the fin *s⁴*. Each operator is preferably provided with two or more of these sending machines, set side by side, and if it be desired to get the buttons closer together, the spring motors may be put on opposite sides. The idea in this duplication is two-fold. In the first place it is necessary to provide a reserve set in case of derangement of the working set, and in the second place the operator must be able to attend to another call, and set up another number, while a number already set up is being transmitted. The period of operation which I have found most suitable is five seconds, that is to say, it takes five seconds for the box to run down after it has been set and wound. It takes the operator approximately three seconds to get the number wanted, and to depress the proper buttons corresponding thereto. Under ordinary conditions therefore it would be advisable to furnish an operator with three machines, set side by side, so that during a busy period, she could take a call and set it up in the first machine, then take another call and set it up on a second machine, then still another on the third machine, and then

again return to the first machine without further delay. The operator has absolutely no work to do in connection with a call except to set up the number and pull the winding lever. Obviously, we can so arrange this sending lever that it can be operated by the foot, or we may employ some other kind of motor, either constantly driven or intermittent, the operating spindle s being coupled thereto or the motor started by depressing a suitable button or the like when the number has been set up. It will be observed that the saving in time consumption is very large, since, according to the best manual practice the average time consumed in completing a connection is approximately eleven seconds.

I will now describe my circuit arrangements shown in Figs. 7 and 8. In Fig. 7 A is a subscriber's station equipped with common battery apparatus, and connected by line wires 1-2 to the central office, where it normally passes on the one side to the line relay M and on the other side to ground. The line relay controls a lamp m . Extensions 3 and 4 of the line lead from front contacts of the cut-off relay N to the jack J , or to the equivalent multiple contacts in a primary selector switch to which reference will be made hereinafter. A plug P cooperates with the jack J and is connected by cord conductors 5 and 6 through condensers D to trunk wires 7-9 and 8-10 leading to the automatic switches in Fig. 8. Interposed in the trunk wires referred to are the normally closed contacts 11-13, 12-14 of a key K , having other contacts 15-16 connected by wires 17-18 to the sending machine. A listening key K' when actuated connects the operator's telephone O to the wires 7-8. With the key K in the normal condition shown, the cord conductors and trunk wires are continuous for purposes of conversation from the plug P through to the switches. When the key K is thrown down, the wires 7-9, 8-10, are respectively broken, 9 and 10 being then connected individually to the wires 17-18. The wire 17 passes to the armature of a relay k , and when the armature of the said relay is retracted, the connection is completed to the battery B . The relay has its windings connected in the circuit 19 passing through a switch 20 to the spring c of the sending machine. The spring c' , as already stated, is connected to the frame of the machine and thence to the different sets of key stems p^2 . I have indicated this connection by a wire 27 and have indicated the electrical connection between the wheel W and the fins s' , s^2 , s^3 and s^4 by the line 21.

The reason for introducing the relay k between the springs c and the circuit over which the impulses are to be transmitted is simply to change the breaks produced at the

wheel into makes or current impulses, because it is easier to operate the type of switches I have chosen for illustration on makes than on breaks. The wire 19 might be connected directly to the wire 17 without changing the operation essentially. Inasmuch as I have shown the relay k on a normally closed circuit however, I introduce the switch 20 so that current may be cut off from the relay when desired or when the machine is not in use.

The set of automatic switches shown in Fig. 8 is the same as that illustrated and described in my prior application, Serial No. 279,031, filed September 18, 1905, and is also the same as any set of standard "Strowger" switches. The mechanical construction of such switches is clearly shown as to the selectors in Letters Patent No. 815,321, granted March 13, 1906 to Keith and Erickson, and as to the connector switches in Letters Patent No. 815,176, granted on the same date to the same parties. The testing of the wanted line is performed in the connector switch automatically, and I preferably use automatic ringing also which I have illustrated herein. I wish it to be understood, however, that I also contemplate employing in this same circuit the method of ringing shown and described in my application hereinbefore referred to in which case the operator will have a suitable ringing key with normally open contacts adapted to connect the wire 9 to battery when actuated, so as to send impulses at will over the vertical trunks 22, etc., to the vertical relay which after the side switch has taken its final step is usually employed to control the ringing relay. The operator's key for this type of ringing is shown at the right of Fig. 8, and the modified connector circuit cooperating therewith is shown in Fig. 8^a, the rest of the switch circuits being identical with those of Fig. 8.

In operation, the switches I have here illustrated respond to selective groups of impulses coming over the wires 9 and 22, the number of impulses in each group being determined by the particular buttons depressed in the sending machine. The controlling rotary impulses for the switches are sent over the wires 10 and 23 through the springs c^2 , c^3 of the sending machine.

In operation, the calling subscriber A removes his receiver from the hook, closing his line circuit and energizing the line relay so as to light the lamp m . The operator inserts the answering plug P in the jack J , and throws down both keys K and K' . Key K' connects her telephone to the calling end 125 of the trunk 7-8; and key K breaks the trunk continuity, putting the wires 9-10 on to the wires 17-18 of the sending machine. Having received the number wanted, the operator sets it up on the buttons P' , 130

P_2 , P_3 , P_4 , as already described, and pulls her winding lever. The number groups of impulses are then transmitted over the wires 17, 9 and 22 to the switches, and the rotary 5 or controlling impulses over wires 18, 10 and 23 as already described. The key K is left down until the winding arm has reached its extreme position of rest, when the operator then throws up the key K and 10 uses the same sending machine for another trunk and another call. The circuit 17-18 is branched for this purpose to other keys K as indicated at 24-25. According to this arrangement there would be one key K for 15 each trunk, but obviously I may combine all of these keys in one common switch with movable contacts for the terminals of wire 17-18, and fixed terminals such as jack springs or the like for the trunk wires. 20 Various other switching arrangements may be made and it is to be understood that I include the same broadly as within the scope of my invention.

Having thus described my invention what 25 I claim as new and desire to secure by Letters Patent is—

1. An impulse signal transmitting device for use in telephone exchange systems comprising means for producing uniform groups 30 of current impulses, and means for modifying the groups becoming operative during transmission, said means comprising separate contact units arranged in digital groups corresponding to the groups of current impulses, substantially as described.

2. An impulse signal transmitting device for use in telephone exchange systems comprising a number wheel adapted to produce a uniform series of current changes, a plurality 40 of rows of push buttons corresponding to variable digits of the number to be transmitted, interlocking means for the push buttons in each row and means operated with the number wheel as determined by the buttons to modify the current changes in accordance with the number to be transmitted, substantially as described.

3. A signal transmitter for use in telephone exchange systems, switching apparatus comprising uniformly proportioned means for producing uniform groups of control impulses, and means for modifying the groups becoming operative during transmission, said means comprising separate contact units arranged in digital groups corresponding to the groups of current impulses, substantially as described.

4. An impulse transmitter to be used in telephone exchange systems comprising means to produce uniform groups of impulses, and a plurality of banks of signal selecting keys each comprising a plurality of keys and arranged to short-circuit said impulse producing means during various portions 60 of the operation thereof according to

the key of the bank pressed whereby various portions of each group of impulses may be made effective to control the switches.

5. An impulse transmitter to be used in telephone exchange systems comprising means to produce successively a plurality of uniform groups of signal impulses, and a corresponding plurality of banks of digitally arranged signal selecting keys, arranged to successively disable said impulse producing means during the production of a portion of the corresponding group of impulses whereby the groups of impulses are variously modified during transmission.

6. An impulse transmitter to be used in telephone exchange systems comprising a rotary device for producing uniform groups of impulses, and a concentrically arranged bank comprising a plurality of signal selecting keys arranged to disable said impulse producing device during the production of various portions of the groups of impulses according to the key of the bank which is operated whereby the groups of impulses are variously modified during transmission.

7. An impulse transmitter to be used in telephone exchange systems comprising a rotatable commutator device arranged to produce uniform groups of signal impulses, 95 concentrically mounted angularly displaced switching segments, and a bank of co-operating signal selecting keys associated concentrically with each switching segment and arranged to disable the commutating during the production of various portions of the groups of impulses whereby the groups of impulses are variously modified during transmission.

8. A signal transmitter for use in telephone exchange systems comprising a rotatable wheel having contacts associated therewith by means of which it produces signal impulses of predetermined number and frequency in cycles, together with a plurality 105 of groups of rotary switching devices adapted to excerpt from each cycle of impulses produced by said commutator wheel groups of impulses varying in number, each of said switching devices comprising a fixed bank 110 of push button contact keys and a co-operating rotary contact cam.

9. A signal transmitter for use in telephone exchange systems comprising a rotatable wheel having contacts associated therewith by means of which it produces signal impulses of predetermined number and frequency in cycles, together with a plurality 120 of groups of rotary switching devices adapted to excerpt from each cycle of impulses produced by said commutator wheel groups of impulses varying in number, each of said switching devices comprising a fixed bank 125 of push button contact keys and a co-operating rotary contact cam, together with an 130

6
interlock between the individual keys of each bank whereby but one key at a time may be depressed.

10. A signal transmitter for use in telephone exchange systems comprising a toothed disk, a pair of fixed contacts actuated through the rotation of said disk to produce current impulses, a plurality of angularly spaced synchronously rotated cam contacts, a plurality of banks of concentrically arranged coöperating signal selecting keys arranged to be contacted with by

said cam contacts in their rotation, together with interlocking means between the individual keys of each bank and circuit connections closed by said cam and key contacts in shunt to said fixed contacts actuated by the toothed wheel. 15

In testimony whereof I affix my signature in presence of two witnesses.

EDWARD E. CLEMENT.
